ELECTRON DISCHARGE TUBE

Clark H. Sphar, San Francisco, Calif., assignor to
Heintz & Kaufman, Ltd., South San Francisco,
Calif., a corporation of Nevada

Application January 27, 1942, Serial No. 428,373

1 Claim. (Cl. 250—27.5)

My invention relates to electron discharge tubes, and more particularly to a means for supporting electrodes within such tubes from the walls of the envelope.

Among the objects of my invention are:

To provide an electron discharge tube wherein the elements are supported therein by a girder construction; to provide a means for supporting the elements of an electron discharge tube in such a manner as to minimize relative movements between electrodes; and to provide a strong sturdy and simple electrode support for elements to be positioned within an envelope.

Other objects of my invention will be apparent or will be specifically pointed out in the description forming a part of this specification, but I do not limit myself to the embodiment of the invention herein described, as various forms may be adopted within the scope of the claim.

My invention may be more fully understood by direct reference to the drawings, wherein:

Fig. 1 is a view in side elevation of one preferred embodiment of my invention as applied to a vacuum tube of the transmitting type.

Fig. 2 is a view partly in section and partly in elevation showing the electrodes of the tube of Fig. 1 in detail.

Fig. 3 is a sectional view taken as indicated by the line 3—3 in Fig. 2.

Fig. 4 is a view partly in section and partly in elevation taken as indicated by the line 4—4 in Fig. 2.

Referring to the figures for a detailed description of a preferred form of my invention, as illustrated—an envelope 1, preferably of glass, such as heat resisting glass, is provided at one end thereof with a reentrant stem 2 having an inner press 3, through which pass a pair of filament supports 4. Filament supports 4 are provided outwardly with flexible conductors 5 which are connected to contact pins 6 forming a part of a base 7 applied to the stem end of the envelope.

Immediately above the stem end of the envelope is positioned an enlarged portion of the envelope 9 terminating in an anode end 10 to which an anode cap 11 is sealed by a metal-to-glass seal flange 12. The outer end of anode cap 11 is provided with a large anode contact pin 14. The inner end of the cap is projected into the bulbous portion of the envelope as a tube 15. Tube 15 has attached thereto a plurality of radially and downwardly extending anode support elements or girders 16, these elements preferably being of U-section, the lower ends being attached to fins 17 of a cylindrical anode 18.

Anode 18 is provided at the top thereof and between support elements or girders 16 with a dome-top 20 having a central aperture 21. On one side of the tube, preferably adjacent the connection of the bulbous portion 9 to the stem portion of the envelope, is a grid envelope arm 22 outwardly terminated by a grid cap 23 sealed to the arm 22 by a metal-to-glass seal flange 24. As with the anode seal, the outer end of the grid cap 23 is terminated by a grid contact pin 25, the grid cap being projected inwardly, concentric with arm 22 as a grid support tube 26.

Grid support tube 26 has welded thereto on opposite sides thereof, side-by-side girders 27 preferably of U-section, these girders diverging toward the interior of the tube to terminate, as by welding, on a grid base 28. Grid base 28, as will be seen in Fig. 2 supports a plurality of grid-wire hairpins 30 having parallel vertical runs, these hairpins being joined at the top to form a domed inner end 32 of the grid. Filament supports 4 extend upwardly inside grid base 28, and have semi-circular cathode connectors 33 and 34 welded to their respective upper ends. These connectors make conductive contacts, as by welding, with a plurality of upright filaments 35 welded to a disc 36 sliding on a central filament support rod 37 embedded in the stem press between filament supports 4. Filament disc 36 is supported by a pair of disc rods 38 extending upwardly inside the filament assembly, these disc rods being attached together at their lower end and to a spring disc 39 also sliding on rod 37. Spring disc 39 is forced upwardly, to keep the filaments under tension by means of spring 40, bearing at its lower end against second spring disc 41 supported on a pair of spring positioning members 42 tied together by rivets or small screws 43, with insulating material such as mica between each half and each filament support 4. In this manner the filament spring is kept well out of the heated portion of the tube, and therefore will maintain filament tension under continuous operation of the tube. Tension on the spring may be adjusted by varying the position of clamp 42.

It will be noted that neither the anode nor the grid, which are the electrodes of greatest weight in the tube, are dependent upon wire supports. They are both supported from tubular elements, sealed to the tube envelope over a wide extent thereof, thus forming firm basis for the support of both anode and grid. Tubular supports of both anode and grid are extended to support the anode and grid by means of spaced girder bars, preferably of U-section. It is also to be noted that the

grid is supported by the tube 26 and the girders 27 at an angle to both the vertical and horizontal, thus enabling the grid to more fully withstand shocks, than if the grid supports were extended only horizontally. Lateral and twisting movements of the grid is reduced by the box arrangement of girders. Both grid and anode supports involve triangular arrangements of elements and are thus made exceptionally sturdy and resistant to displacement, the triangle being recognized as representing the most rigid of the simple geometric figures. Small relative displacements of the elements are avoided, leading to efficient and proper operation of the tube, particularly at high frequencies.

15

I claim:

In an electrical discharge tube having a glass envelope and electrodes therein to be supported by said envelope, an electrode support comprising a cylindrical conductive member projecting through said envelope, a metal flange extending laterally around said member intermediate the ends thereof and having the periphery thereof sealed to said envelope, a plurality of spaced girders extending from the inner end of said member symmetrically with respect to the axis of said cylindrical conductive member, and an electrode attached to said girders.

CLARK H. SPHAR.
